UNITED STATES PATENT OFFICE.

WALTER H. NEWMAN, OF BUFFALO, NEW YORK.

DOUBLE-SLIP-SWITCH FITTING.

Application filed February 9, 1923. Serial No. 618,018.

To all whom it may concern:

Be it known that I, WALTER H. NEWMAN, a citizen of the United States of America, residing at Buffalo, in the county of Erie 5 and State of New York, have invented certain new and useful Improvements in Double-Slip-Switch Fittings, of which the following is a specification.

This invention relates to the construction 10 of the parts used for bracing the switch points and connecting operating mechanism thereto, such parts being commonly known as switch fittings, and more particularly to such switch fittings for double slip switch 15 layouts.

Switch fittings are subjected to severe 20 stresses, adverse weather conditions, and heavy shocks and jars by passing equipment, so that it becomes a somewhat difficult problem to design an arrangement and combination of parts for switch fittings which in practice affords the necessary degree of flexibility and rigidity, permits ready adjustment, and altogether withstands the hard 25 usage to which it is subjected. A certain degree of flexibility is essential, because of movements of the rails and switch points from time to time, such as "creeping" of the rails, and the displacement occurring in 30 the regular operation of the points. On the other hand, it is highly important to hold switch points, particularly the closed point, firmly and tightly to keep these points from rolling from the proper vertical position. It 35 is also desirable to maintain a certain definite spacing between each pair of switch points, so as to bring the closed point in proper position for the different positions of the switch. Finally, it is very desirable, 40 from a practical standpoint, to afford simple and effective provisions for relatively adjusting the switch fittings, such adjustment being made in such a way that it is permanent when once made. In addition to 45 these features, it is important to provide a structure for insulating the pairs of points from each other and electrically segregating the points of each pair, so that the usual detector track circuits may be carried 50 through the switch layout with a minimum amount of insulating material and with the least possibility of derangement.

Generally speaking, the objects of the present invention are to provide a simple, inexpensive and effective structure satisfying 55

the requisites for a practical device, some of which have been outlined above. Various specific features and advantages of the construction embodying this invention will be pointed out in detail hereinafter. 60

In the accompanying drawing, Figure 1 is a fragmentary plan view of a conventional double slip switch layout and shows the switch fittings embodying this invention applied thereto; 65

Fig. 2 is a vertical transverse section through the switch layout, showing in elevation the front rod and adjustable connections to the lock rod;

Fig. 3 is a detail section on the line 3—3 of Fig. 2; 70

Fig. 4 is a fragmentary detail view showing more particularly the adjustable connection between the front rod and one of the switch lugs or feet; 75

Fig. 5 is a fragmentary view showing a modified construction of switch lug for connecting the front or number one rod to the outside of the switch points; and

Fig. 6 is a fragmentary detail section on the line 6—6 of Fig. 5. 80

Referring to the accompanying drawing, the invention has been shown applied to a conventional double switch layout, comprising the main stock rails 1 and 2, and the two pairs of movable switch point 3—3^a and 4—4^a. Such a switch layout, being well-known in the art and in common use, requires no detail description. The invention is shown applied to the front rod F 85 at the extreme ends of the switch points and to the intermediate rod O, commonly known as the number one rod. The only substantial difference between the construction for the front rod F and the number one 90 rod O is in the adjustable connection between the lock rod and the throw rod respectively connected thereto. The throw rod and the lock rod may be connected to a mechanical switch and lock movement, or a power operated switch machine; and since these features correspond to recognized practice, no particular arrangement has been shown.

As illustrated, the throw rod 5 is connected 100 by a suitable adjustable connection or basket 6 to the number one rod O in the usual way. This number one rod and the construction of those connections to the switch points is the same as that of the front rod F, consequently it will be sufficient to describe 105 110

the construction of the front rod F alone in detail.

The front rod F comprises a bar 7, of greater width than thickness, which extends 5 clear across the switch layout with an interposed insulated connection 8 near the middle between the inner switch points 3^a and 4. In effect, therefore, this bar 7 is made up 10 of two lengths fastened together at their adjoining ends by an insulated connection 8. This insulated connection 8 may be made in any suitable manner, but is preferably constructed as shown with two plates, bolts, fiber sheets and insulating bushings, 15 all in a manner well known in the art. Referring to Figs. 1 and 2, it will be noted that the bar 7 is disposed on edge at the intermediate point of its length, that is, with its widest dimension vertical, while at the 20 ends the bar 7 is disposed flatwise, said bar being given a half twist at a point approximately midway between the pairs of switch points, as shown.

The bar 7 is connected at its ends to the 25 two outer points 3 and 4^a by switch feet or lugs 9. Each of these lugs 9 is a forging or malleable iron casting with a portion extending parallel with and bolted to the switch point, and having another portion 30 curved downward and formed with upper and lower bifurcations 9^a (see Fig. 3) straddling the rod 7. Riveted to the rod 7 is a perforated ear 10, which together with the rod 7 having a hole therein forms a clevis; and 35 through this ear, the bifurcations 9^a, and the rod 7 passes a bolt 11.

The connections of the inner switch points 3^a and 4 to the bar 7 are the same. In this instance, the switch lug or foot 12 40 consists of a flat bar rectangular in cross-section, preferably a forging, which is disposed at one end flatwise and parallel to the switch point and is bolted thereto in the usual way. This lug 12 then projects forwardly beyond the point, as shown in Fig. 1, and then is curved downwardly as shown in Fig. 2 and extended alongside of the bar 7. The end of this lug 12 is screw-threaded and passes through a hole in an angle 45 bracket 13 rigidly fastened, as by rivets, to the bar 7. The lug 12 is disposed on edge, that is, with its longest dimension vertical, and the angle bracket 13 is similarly disposed with its longest dimension vertical. This vertical disposition of the bar 7 and 50 the switch lugs 12 affords a high degree of stiffness and rigidity, and at the same time economizes in space, so that said bar 7 and the horizontal portion of the lug 12, while having adequate dimensions for strength, 55 may be disposed relatively close together.

The lug 12 is adjustably connected to the bracket 13 by nuts 14. With this adjustable connection, it is preferred in practice to 60 have these pairs of nuts 14 separated to a

small extent, say one-sixteenth to one-eighth of an inch further than the thickness of the bracket 13, so as to afford a slight lost motion (as best shown in Fig. 4). By reason of this lost motion, the lug 12 may move up 70 and down to a limited extent, pivoting or rocking at its point of connection to the bracket 13.

The lock rod 16 has one end threaded and 75 adjustably connected by pairs of nuts 17 to an angle bracket 18, which is riveted to the bar 7. This angle bracket 18 is also disposed on edge as shown.

Among the various advantages of this 80 particular construction just described, it will be noted that the adjustable connections between the inner switch points 3^a and 4 and the front rod F, and also the number 85 one rod O, are readily accessible and are so disposed that a wrench may be easily applied to the adjusting means. More particularly, this accessibility is due to the fact that the switch lugs 12 are disposed vertically at one side of and parallel to the bar 7 so that without destroying stiffness 90 and rigidity, or extending beyond the available space, there is sufficient separation of these two parts to permit a wrench to be readily applied without any interference. In this connection, it should be understood 95 that certain dimensions or clearances are determined by the switch layout itself. For example, the space between the tips or front ends of the inner points 3^a and 4^a is fixed and any connections or adjustments within 100 this restricted space will necessarily in practice be inaccessible and difficult to adjust.

It should also be noted that the switch lugs 12, being disposed edgewise, may more 105 easily be passed by each other by moving one or the other forward or backwards lengthwise of the track, than if disposed flatwise. The removal of these switch lugs 12 is consequently much facilitated, the limited space between the tips of this space 110 3^a and 4 necessitating such bypassing or overlapping if the switch lugs are to have adequate strength. It will be noted that the switch lugs are curved down on a relatively 115 large radius, so that there are no sharp curves or bends to break under localized stresses.

Another characteristic feature of the invention is the provision of a single insulation 120 at a point where the thrust or stress to which it is subjected may be most easily taken care of. The insulated connection 8, it will be observed, not only insulates the point 3 from the point 3^a and the point 4 from the point 4^a, but also the pair of points 125 from each other. The thrust or stress in the rod 7 is largely a direct longitudinal pull or push; and experience has demonstrated that an insulating connection can be very effectively made in a simple and in- 130

expensive manner between two members subjected to such stresses. The use of a single insulated connection 8 minimizes the number of insulation points to be inspected 5 and maintained.

All of the necessary adjustments are afforded by the construction described. The connections between the throw rod 5 and the lock rod 16 are adjustable to an accurate degree by a screw-threaded arrangement, so that the position of the outer switch points 3 and 4^a, when closed points, may be accurately fixed. The inner points 3^a and 4 are likewise adjustably connected to the bar 7, thereby permitting the position of these points, when a closed point, to be accurately determined. To illustrate, referring to Fig. 1, the position of the switch point 3^a against the stock rail may be accurately adjusted by the nuts 14. It should also be observed that each of the adjustments provided may be made separately and independently without disturbing any other adjustment.

In the modified construction shown in Figs. 5 and 6, the bar 7 is maintained on edge throughout its length, instead of being disposed partly on edge and partly flatwise, as in Figs. 1 and 2; and the connection between the bar 7 and the outer switch points 3 and 4^a is made by a modified form of switch lug or foot 19, also disposed edgewise so as to afford a maximum degree of stiffness and rigidity, particularly holding the points against rolling or turning over. This lug 19, as clearly shown, has one portion extending parallel to the web of the switch point and bolted thereto, and another portion curved downwardly on a relatively large radius and extending parallel with the bar 7. The connection between the lug 19 and the bar 7 is made by a bolt 20 in a way that will be obvious.

While certain specific forms and shape of parts, and a particular disposition or arrangement, have been selected and hereinbefore shown and described to illustrate the nature of this invention, it should be understood that various modifications and adaptations may be made in this particular construction and arrangement without departing from the scope of the invention. I desire to have it understood, therefore, that the invention is not limited to the particular construction and arrangement shown.

55 What I claim is:—

1. A double slip railway switch and fittings therefor comprising, two pairs of stock rails, two pairs of switch points associated with said stock rails, a switch rod extending transversely of and below said stock rails and switch points, and means lying in the same horizontal plane with said rod and spaced a considerable distance therefrom and adjustably fastened thereto for adjustably connecting said rod to one of said switch points.

2. A double slip railway switch and fittings therefor comprising, two pairs of stock rails and associated switch points, a switch rod extending transversely of and below said stock rails, a perforated bracket extending 70 horizontally from said rod, means adjustably fastened in the perforation of said bracket extending substantially parallel to said rod for a considerable distance from whence it is bent upward and back upon itself and 75 parallel to one of said switch points, and means for connecting said last mentioned means to said switch points.

3. A double slip railway switch and fittings therefor comprising, two pairs of stock 80 rails and associated pairs of switch points, a switch rod extending transversely of and below said stock rails, a perforated bracket extending horizontally from said rod, a U-shaped piece of strap iron lying substantially parallel to said rod and having one of its legs bent sidewise and bolted to one of said points and having its other leg threaded and adjustably fastened in the perforation of said bracket.

4. A switch fitting comprising, a piece of strap iron of rectangular cross-section bent edgewise to form a U and having one of its legs perforated and bent sidewise, and a threaded extension formed integral with the 95 other end of said U-shaped strap iron.

5. A double slip railway switch and fittings therefor comprising, two pairs of stock rails each pair having a pair of switch points associated therewith, a switch rod of rectangular cross-section disposed transverse to said stock rails and switch points and disposed in a vertical plane throughout its length except at its ends which are twisted 100 to dispose them horizontally, means for fastening the horizontally disposed ends to two of said switch points, and means for fastening the vertically disposed portion of said rod to the other two switch points.

6. A double slip railway switch and fittings therefor comprising, two pairs of stock rails and associated switch points, said two pairs of rails being so disposed with respect to each other that one rail of each pair is located between the rails of the other pair, a switch rod for operating both pairs of switch points simultaneously disposed transversely with respect to said rails and having an insulating joint near its middle, a mechanical connection on each side of said insulating joint to one of the switch points of each pair, whereby a single insulating joint will insulate each pair of switch points from each other.

7. A double slip railway switch and fittings therefor comprising, two pairs of stock rails each pair having a pair of switch points associated therewith, a switch rod of rectangular cross-section disposed transverse to said stock rails and switch points and dis-

posed in a vertical plane throughout its length, curved angle brackets fastened directly to said switch rod each having its other end fastened to one of the outside switch 5 points, and adjustable means for adjustably fastening the other two switch points to said switch rod.

8. In a railway slip switch, the combination with a pair of stock rails a pair of switch 10 points associated therewith, a switch rod of rectangular cross-section disposed generally vertical and crosswise of said rails and points, said rod being twisted so as to dispose its end horizontally, a flat perforated ear fastened to said rod adjacent a hole in said rod 15 to form a clevis, a bifurcated perforated lug fastened to one of said switch points and pivotally secured to said clevis, and means for adjustably fastening the other switch to the vertically disposed portion of said switch rod.

9. A double slip switch and fittings therefor comprising, two pairs of stock rails so arranged that one rail of each pair is between the rails of the other pair, two pairs 20 of switch points associated with said rails, a switch rod rectangular in cross-section disposed generally vertically and extending transversally of said rails and points, said rod being twisted so as to be disposed horizontally at its ends, means for adjustably connecting two of said points to the vertically disposed portion of said rod, and means for pivotally securing the other two switch 25 points to the horizontally disposed portion of said rod, said last mentioned means comprising two pairs of inter-engaging perforated bifurcated members.

10. A double slip switch and fittings there- 40 for comprising, two pairs of stock rails so ar-

ranged that one rail of each pair is between the rails of the other pair, two pairs of switch points associated with said rails, a switch rod rectangular in cross-section disposed generally vertically and extending transversally 45 of said rails and points, said rod being twisted so as to be disposed horizontally at its ends, two oppositely disposed hook shaped switch lugs bent edgewise and having their ends disposed transversally for connecting the two middle switch points to the vertically disposed portion of said switch points to the horizontally disposed portion of the switch rod.

11. A double slip switch and fittings there- 50 for comprising, two pairs of stock rails so arranged on the usual ties that one rail of each pair is between the rails of the other pair, two pairs of switch points associated with said rails, a switch rod rectangular in cross-section 55 extending transversally of said rails, said rod being shorter than the distance between the two outside switch points and being vertically disposed except that its ends are twisted so as to dispose them horizontally, means for pivotally securing the horizontally disposed ends of said switch rod for movement about a vertical axis to the outside switch points, and means for adjustably 60 securing the two middle switch points to the vertically disposed portion of said switch rod, whereby a construction is formed in which the greater part of the switch rod is vertically disposed to resist rolling of the switch points and in which the ends are 65 horizontally disposed to facilitate the provision of pivotal connections.

In testimony whereof I hereby affix my signature.

WALTER H. NEWMAN.
